UNITED STATES PATENT OFFICE.

JESSE ALEXANDER, OF LOS ANGELES, CALIFORNIA.

RIBBON-OPERATING MECHANISM FOR TYPEWRITING MACHINES.

Application filed November 5, 1923. Serial No. 672,822.

My invention relates to ribbon operating mechanism and particularly for the front stroke visible class of writing machines.

The main objects are to provide a simple and inexpensive mechanism which will operate with little power and yet is very compact, easy to assemble and unlikely to get out of order.

The ribbon is fed from a spool or bobbin at one side of the machine to a spool or bobbin at the other side.

Beneath the type bars to the front of the machine is a cross bar which connects to upright arms and by moving a thumb lever which connects to one of the upright arms, causes the arms to shift thereby throwing the driving pawl in on one side and out on the other, at the same time releasing the spring pressed back stop which allows for the reversing of direction.

The feeding action is accomplished by the step by step rotation of the carriage tension drum as it is released by the escapement. The universal bar is also located beneath the type bar printing point and contacts with a point on the type bar just above its fulcrum point which actuates the universal bar. The lifting of the ribbon to the printing point and its retraction is accomplished by the action of the universal bar.

One form of the invention is shown and illustrated in the accompanying drawings.

The mechanism is adapted to perform what is known as two-color or two-ink work. The ribbon is provided with two kinds of ink or two colors of ink, the upper edge for instance, being red, and the lower edge of the ribbon being black. The change from one to the other is accomplished by the pressing in or pulling out of the knob at the side. Also the ribbon can be left in normal position by pushing the knob to the central notch for the purpose of stencil work, leaving the type free and clear to cut their impressions in the stencil.

The invention consists in the movements and principles of which are illustrated in the accompanying drawings, as will be more fully understood from the following specifications.

Fig. 1 is a plan view of a typewriting machine embodying my ribbon movement and showing detailed views of the universal bar,

the shifting mechanism and the driving and holding pawls and portions of the drive wheels and arrangement for shifting for two colored ribbon print and stencil work.

Fig. 2 is a sectional view showing the arrangement for shifting the ribbon holder in order that it may print on the bottom, or lift it so that it will print on the top of the ribbon or leave it in a neutral position so that it neither lifts or prints, but leaves the face of the type free to cut stencils.

Fig. 3 is a sectional view of the ribbon movement showing the rock shaft with the extended arm carrying the driving pall, the ratchet wheel back stop, ribbon shifter and thumb piece for shifting to either spool, and releasing the opposite spool.

Fig. 4 is a sectional view looking from the back of the machine towards the front showing the cross bar and its connection to the upright releasing arms, the ribbon guide and lift, the ribbon wheels and the spring pressed lock holding the wheels on.

Fig. 5 is a detailed sectional view showing the universal bar swing and its connection to the rock shaft through a post and a portion of the ribbon guide lifting arm.

Fig. 6 is a sectional view of a typewriting machine embodying my ribbon movement showing the universal bar, its connection to the rock shaft the drive posts of the ribbon driving pall the ratchet wheel the back stop pawl the upright releasing arms, the ribbon holder and the ribbon lifting arm with the key and type bar movement.

Fig. 7 shows the finger piece and the spring with a projection on for shifting the ribbon to either spool and holding same in contact in either position.

The ribbon is mounted on suitable spools or bobbins 1 and is driven through my key and type bar action and its co-related parts which are more fully described in my accompanying application, Serial No. 672,823, filed Nov. 5, 1923.

The key and type bar action is shown in Fig. 6 in normal position.

The key lever 2 is pivoted in rear of the machine at 3 and has a slot and stud connection 4 with the forward arm of the intermediate lever 5, said intermediate lever 5 is pivoted at 6 and its upward extending arm 7 is pivoted to draw link 8. Draw link 8 is

pivoted to the rear and downward portion of type bar 9 with stud and slot connection 10.

Type bar 9 has a shoulder or bearing 11 which contacts with universal bar 12, the universal being fixed to a support 13 as shown in Figs. 1 and 6. The depression of the key lever 2 drives the type bar against the universal bar so as to move the universal bar and its support 13 backwards against the spring 14, thereby rocking shaft 52 which is journaled in sleeve 15, through its connection with post 16. Post 17 fixed to shaft 52 and connected to drive pawl 18, is in turn driven forward thereby driving ratchet wheel 19 the distance of a tooth. The slot and pin 20 hold driving pawl 18 in position and also carries compression spring 21, in Fig. 4. The sleeve 15 in which shaft 52 is journaled is preferably mounted in the typewriter frame so that the rock shaft is below the universal bar support 13.

By the release of the finger lever 2 the type bar 9 returns to normal releasing its pressure on the universal bar, thereby allowing the universal and its support 13 to return to normal position through compression spring 14 at the same time returning driving pawl 18 to its normal position.

This revolves ratchet wheel 19 which has a shaft 22 carrying ribbon spools 1 and driving same step by step, in order to take up any back motion and to hold the ribbon in proper position I provide a spring pressed back stop pawl 23 which engages the ratchet wheel 19 and has an extended portion 24 which contacts with a tooth 25 in upright arm 26 as shown in Fig. 1. Tooth 27 in upright arm 26 contacts with drive pawl 18. Finger piece 28 is mounted on frame 29 on shaft 30 and carries a lug 31 which has a slot and pin connection 32 with the upright arm 26. Fig. 7 shows the thumb piece 28 and a V-shaped compression spring 33. By moving the thumb piece 28 to one side of the V will in turn move the upright arm 26 to the opposite direction allowing the driving pawl 18 to be held in contact with ratchet wheel 19 for driving and allowing back stop pawl 23 to contact holding ratchet wheel 19 in position, at the same time holding driving pawl 18 and back stop pawl 23 out of engagement with the opposite ratchet wheel through the releasing arm 26. The releasing arms 26 are pivoted at 34 and have a cross bar 35 pivoted at 36, therefore it can be seen that by moving thumb piece 28 in either direction it will at the same time move the upright arms 26 through their connection with the cross bar 35 and in turn release one of the ratchet wheels 19 of its engagement with the driving and back stop pawls and re-engage it with the opposite side.

37 is a push button carrying a shaft 38

Fig. 1. Said shaft has three position notches 39 and carries a link 40 connecting a slide 41 which is mounted in the under side of the universal support 13 in rear of rock shaft 52. The slide 41 is connected to 70 the universal bar support 13 by means of a slot and pin connection 42; and the slide has two projections or pins 43—44 vertically spaced and adapted to selectively engage in a slot 45 provided in the upwardly curved 75 rear end of a ribbon guide lifter 46 so as to exert different leverage on the lifter. The ribbon guide lifter is pivoted at 47 to the typewriter frame below the universal bar support 13 and in rear of rock shaft 52, and has a forward lifting arm curving around the rock shaft and provided with a pin and closing slot connection 60 with the ribbon lifting guide 48. By moving the knob 37 to the extreme right it will place the projection 43 in the slot 45, thereby causing the ribbon to lift a greater distance. By reversing the position and moving the knob to the extreme left, it will place projection 44 in the slot 45, thereby causing the ribbon 90 lift guide to lift a lesser distance. By placing the knob so it is held in the central notch or central position notches 39 Fig. 2 it will leave the projections 43—44 free of the ribbon lifting guide 45 as shown in Fig. 2 95 thereby allowing the type bar to move to the printing point without lifting the ribbon.

The ribbon spools are held in position by arms 49 which are pivoted at 50. The ribbon spools or bobbins 1 are placed slightly 100 above the ribbon lifting or holding guide 48 in normal position in order that when in action the ribbon will be in a straight line for the print of the type.

The ribbon lifter is positioned by three 105 points of contact as shown in Fig. 2. The points of contact are 39 and are held in either position by a spring pressed wire 54. By forcing the knob in either direction the wire will give sufficient to let knob move 110 and will then drop into the next notch, and the outside movement is limited by the slots and pin connection 42 on the universal bar.

Having thus described my invention, what I claim and wish to have protected is this:— 115

1. In a typewriter, a universal bar, a support for the universal bar, means for actuating the universal bar and its support, a rock shaft below the universal bar support and actuated thereby, ribbon feeding 120 mechanism actuated by said rock shaft, a ribbon lifter, a lifting arm pivoted intermediate of its ends below the universal bar support and in rear of the rock shaft, one end of the lifting arm curving around the rock 125 shaft and having a connection with the ribbon lifter, a slide on the universal bar support in rear of the rock shaft, and pins on said slide, the opposite end of the lifting arm curving upwardly and having a slot 130

adapted for engagement by the respective pins by shifting the slide relative to the universal bar support, and said pins being spaced to exert different leverage on the lifting arm.

2. In a typewriter, a universal bar, a support for the universal bar, means for actuating the universal bar and its support, a rock shaft below the universal bar support and actuated thereby, ribbon feeding mechanism actuated by said rock shaft, a ribbon lifter, a lifting arm pivoted intermediate of its ends to the typewriter frame below the universal bar support and in rear of

the rock shaft, one end of the lifting arm 15 curving around the rock shaft and having a pin and closed slot connection with the ribbon lifter, a slide on the underside of the universal bar support in rear of the rock shaft, and pins on said slide, the opposite 20 end of the lifting arm curving upwardly and having a slot adapted for engagement by the respective pins by shifting the slide relative to the universal bar support, and said pins being spaced to exert different 25 leverage on the lifting arm.

In testimony whereof I affix my signature.
JESSE ALEXANDER.
